HOB

Joseph C. Drader, Detroit, Mich., assignor to
Michigan Tool Company, Detroit, Mich., a corporation of Michigan

Application February 4, 1949, Serial No. 74,513

2 Claims. (Cl. 29—105)

1

This invention relates generally to hobs and more particularly it relates to a hob of the general type conventionally used for cutting gears.

The primary object of this invention is to provide a simple, easily constructed hob in which the cutting elements which actually engage the gear blank being cut are separate inserted members locked into the hob body in order that these cutting elements may easily and conveniently be formed of extremely hard material such, for example, as cemented tungsten carbide.

A principal object of the present invention is to provide a hob structure of the general type referred to above, in which each of the cutting elements, which together form the final hob structure, may be of identical form and shape in order that these elements may be easily and conveniently mass-produced, and so that in the event of breakage it will be possible for relatively unskilled workmen to replace a broken tooth section without the necessity of the precise adjustments which might normally be expected.

Still further the invention contemplates a novel inserted tooth hob structure in which novel and improved means are employed for anchoring the cutting elements in place and at the same time in which means are provided for giving adequate support for the cutting elements when mounted in position.

Yet another object of the invention consists in the provision of novel means adapted to engage the axial ends of the respective cutting elements in order that these cutting elements will be accurately and precisely located with respect to each other and with respect to the hob body.

Many other and further objects, advantages and features of the present invention will become apparent from a consideration of the following specification in connection with the accompanying drawing forming a part thereof.

In the drawing:

Figure 1 is an axial end elevational view with parts broken away showing a completely assembled hob of the type to which the present invention relates;

Fig. 2 is a transverse sectional view taken axially through the hob shown in Fig. 1 along the line 2—2 of Fig. 1;

Fig. 3 is a fragmentary view of a portion of the peripheral surface of the hob structure shown in Figs. 1 and 2, taken substantially along the line 3—3 of Fig. 1;

Fig. 4 is an enlarged fragmentary perspective view of a portion of one of the locking caps illustrating in detail the manner in which the locking

2

surfaces thereof are arranged with respect to each other; and

Fig. 5 is a perspective view of one of the wedge elements used for locking the cutting elements in position within the hob body.

It will be readily appreciated that the specific construction illustrated in the drawings and described in detail below is merely one specific embodiment of the invention to which the present application relates, and that numerous and substantial departures from the specific construction shown may be made without departing from the generic spirit of the invention.

With more particular reference to the drawings, the hob construction comprises a generally cylindrical body portion 1 which may be conveniently formed of mild steel and which in the form shown is provided with an axial bore 2 therethrough adapted to receive the arbor (not shown) on which the hob is to be mounted when in use. As is conventional in constructions of this general character, this bore 2 is provided with a keyway 3 which serves to lock the hob body in driving relationship to the arbor.

25 The body portion 1 of the hob is milled away to provide a plurality of equally circumferentially spaced axially extending recesses 4, each of which has adjacent thereto an axially extending supporting rib 5 which serves to provide means for supporting and backing up tooth cutting elements 6. Each of these tooth cutting elements 6 is seated in a stepped portion of the recesses 4 so that its radial position is accurately and precisely controlled.

30 In accordance with the teachings of the present invention each of these tooth cutting elements are formed of identical shape, size, length and thickness so that they are completely and entirely interchangeable one with another, and 40 in the event one becomes broken, a new element may easily and conveniently be substituted therefor.

Means are provided for locking these cutting elements in predetermined position with respect 45 to the hob body. The specific locking construction shown contemplates the formation of the cutting elements of wedge shape in cross section whereby the cutting elements are of progressively increasing thickness from the teeth inwardly to 50 the base thereof. This provides on each cutting element a sloping face 7 which is adapted to be engaged by a wedge element 8, clearly shown in Fig. 5 of the drawing and illustrated in cross section in Fig. 1 of the drawing. Each wedge element is adapted to be anchored in position by

means of a pair of socket screws 9 which may be used to draw the wedge element radially inwardly with respect to the hob.

As is well recognized in the formation of gear cutting hobs, it is necessary that the teeth in each row be slightly axially offset with respect to the teeth in the next adjacent row in order that the ultimate thread of the hob will have the desired lead. It is obvious from the foregoing that for efficient manufacturing operations and to permit mass production of the tooth cutting elements it is essential that all of the cutting elements be identical and interchangeable. Consequently, in order to provide the offset relationship between one cutting element and the next adjacent cutting elements it is necessary to have extremely accurate and precise means for locating the axial position of each of the cutting elements with respect to each other and with respect to the hob body. In order to achieve this result the hob body is provided with a pair of end caps 10 which may be locked in position with respect to the hob body by means of suitable screws 11. These end caps are each provided with an annular axial face portion which comprises a plurality of locating surfaces 12 clearly illustrated in Fig. 4 of the drawing. Each of these locating surfaces 12 lies in a plane perpendicular to the axis of the hob body and each of these end surfaces is adapted to engage the axial end of one of the cutting elements in order that the axial position of each of the cutting elements will be accurately and precisely controlled. The amount of the axial offset between one of the locating surfaces 12 and the next adjacent face is determined by the amount of offset required between the teeth of one row and the teeth of the next adjacent row, which in turn depends both on the lead or helix angle of the hob and also, of course, the number of cutting elements employed.

In assembling the improved composite hob construction described above the cutting elements are each located on their respective seats and the wedges 8 are loosely retained in position by means of the set screws 9, at which time the end caps 10 are mounted in position to accurately position each of the cutting elements in predetermined axial position with respect to the hob body. The screws 11 are then tightened up to anchor the end caps in predetermined position, after which the screws 9 are set to firmly and rigidly lock each cutting element in position against its associated supporting member.

After the hob has been completely assembled, it may be ground to provide the necessary side clearance for each of the teeth and it will be readily apparent that all grinding performed on the hob may be performed in precisely the same identical manner as is the case with conventional hobs. It will be apparent that in order to provide adequate backing for the cutting elements the supporting member 5 may be cut to provide teeth therein so that each of the teeth of each

cutting element is provided with the maximum possible support.

It is readily apparent from the specific embodiment of the invention illustrated in the drawing and described above that many and substantial modifications thereof may be made without departing from the generic spirit and scope of the invention as set forth in the following claims.

What is claimed is:

10. 1. A hob for cutting gears including in combination a body having opposite ends, a peripheral surface and an axis parallel thereto, a plurality of toothed cutting elements, each of identical form and length extending generally axially of said body and releasably anchored in position on the peripheral surface of said body, a demountable member anchored to each end of said hob body, said members serving to engage the ends of said toothed cutting elements and locate the same precisely with respect to the hob body and with respect to each other, said demountable members each having a series of progressively axially offset faces, each of said faces engaging one of said cutting elements and maintaining the teeth thereof in an axially offset relationship to the teeth of the adjacent cutting elements, whereby said cutting elements will each lie in a slightly different axial position with respect to said body and with respect to each other.
15. 2. A hob for cutting gears comprising a body portion having a plurality of axially extending recesses formed therein, a plurality of identical toothed cutting elements one located in each of said recesses, wedge means for locking said cutting elements rigidly in position in said recesses, a cap member for each axial end of said hob, said cap members each having an annular axially extending portion, the axial face of said axially extending portion comprising a plurality of plane surfaces each lying in a plane perpendicular to the axis of the body portion of said hob, one of said surfaces being provided for each of said longitudinally extending recesses, each of said surfaces being spaced axially from the next adjacent surface a distance sufficient to provide the teeth of the hob with the desired lead and means for locking said cap members to said hob body.
